UNITED STATES PATENT OFFICE.

EDWARD LYNN GRIMES AND FRANK PETERSON, OF RED CLOUD, NEBRASKA.

FLY-KILLER.

1,056,535.

Specification of Letters Patent. Patented Mar. 18, 1913.

Application filed May 7, 1912. Serial No. 695,842.

To all whom it may concern:

Be it known that we, EDWARD L. GRIMES and FRANK PETERSON, citizens of the United States, and residents of Red Cloud, in the county of Webster and State of Nebraska, have invented a new and Improved Fly-Killer, of which the following is a full, clear, and exact description.

This invention relates to such household devices as are used for the purpose of exterminating insects, especially flies, and has particular reference to a device of this nature whereby the flies may be disposed of by poisoning.

Among the objects aimed at in this invention are the following: to provide a poisoning device that is simple in construction and operation, cheap to install and use, and which may be disposed out of the way of children or household pets, and to provide a device which is certain in its operation to destroy the flies.

The foregoing and other objects are attained in a preferred embodiment of the invention by means of the devices hereinafter fully described and claimed, and illustrated in the accompanying drawings, in which—

Figure 1 is a perspective view of our device as in use; Fig. 2 is a similar view with the cap or guard removed; Fig. 3 is a perspective detail of the poison pad; Fig. 4 is a plan view of the device complete; and Fig. 5 is a vertical section on the line 5—5 of Fig. 4, the view being on a larger scale.

Referring to the drawings particularly we have shown at 10 a tray or cup of any suitable size or configuration, but adapted to contain a quantity of water 11, said tray being adapted also to be suspended by means of a hanger 12 upon a nail or pin 13 projecting from a wall or other elevated point where the device may be reached by the insects, but will be out of the way of being tampered with undesirably. Within the tray and related thereto in any suitable way as to size or elevation, is provided what we may term a pedestal 14. The pedestal may be formed in any desired manner, but as to the particular formation we do not desire or intend to be limited. Arranged within the pedestal and tray preferably at the center is a tubular magazine 15 which extends down toward the bottom of the tray and serves to support a capillary member or wick 16 whose function is to draw the water 11 upward to the top of the pedestal.

The numeral 17 indicates a pad made of a plurality of layers of fabric or the like stitched at their edge and adapted to contain any suitable dry poison. The pad 17 will be placed upon the top of the pedestal, as shown clearly in Fig. 5, with its central lower portion in contact with the upper end of the wick 16, the moisture from which will be communicated throughout the pad to the poison, making it into a solution so that the insects may be attracted to it and partake of it. Any suitable chemical may be used for this purpose that is found desirable, and the pads provided by the trade in quantities so that a new pad may easily be put in place of the used one at small cost.

The pads are retained in position on top of the pedestal as above described by any suitable guard illustrated at 18 as comprising a reticulated member 18^a carried by a rim 18^b adapted to be slipped upon or otherwise detachably connected to the top of the pedestal, said reticulated member being thus held in close contact with the upper surface of the pad 17 so that the flies may reach through the member 18^a to partake of the poison solution carried by the pad.

Water may be supplied to the tray in any convenient manner, as through the magazine 15 or through an opening 14^a adjacent the pedestal 14.

The several parts of the device may be constructed of any suitable materials and the relative sizes and proportions of the elements thereof may be varied to a considerable extent without departing from the spirit of the invention.

Having thus described our invention, what we claim as new and desire to secure by Letters Patent is:

1. In a fly killer, the combination of a tray adapted to contain water, a pedestal extending upwardly therein, said pedestal being provided with a tubular magazine, a wick extending from the bottom of the tray to the top of the pedestal within said magazine, a fabric poison pad on top of the pedestal and in contact with said wick, and means to removably hold the pad in place, substantially as set forth.

2. In a fly killer, the combination of a tray adapted to contain water, a pedestal extending upwardly above the top of the tray and having a downwardly projecting magazine, a wick supported in said maga-

zine and extending substantially from the bottom of the tray to the top of the pedestal, means to successively supply measured quantities of dry poison to the top of the pedestal and hold the same in position thereon in contact with the moisture supplied by said wick, and a reticulated guard on top of the pedestal removably securing said poison supplying means in position.

In testimony whereof we have signed our names to this specification in the presence of two subscribing witnesses.

EDWARD LYNN GRIMES.
FRANK PETERSON
